CASING FOR AN ELECTRICAL ICE CRUSHER

Angelo C. De Angelis, Fair Haven, N. J., and Eugene J. Casey, New York, N. Y., assignors, by mesne assignments, to Standard Electronics Corporation, Newark, N. J., a corporation of Delaware

Application May 25, 1956, Serial No. 41,650

Term of patent 14 years

(Cl. D89—1)

FIG. 4.

FIG. 2.

Fig. 1 is a perspective view of a casing for an electrical ice crusher, showing our new design;

Fig. 2 is a side elevational view;

Fig. 3 is a rear elevational view; and

Fig. 4 is a bottom plan view.

We claim:

The ornamental design for a casing for an electrical ice crusher, as shown.
